UNITED STATES PATENT OFFICE.

HARRY F. BUSHONG, OF KALAMAZOO, MICHIGAN, ASSIGNOR TO KALAMAZOO LOOSE LEAF BINDER COMPANY, OF KALAMAZOO, MICHIGAN.

TEMPORARY BINDER OR LOOSE-SHEET HOLDER.

No. 890,020.

Specification of Letters Patent.

Patented June 9, 1908.

Application filed March 7, 1907. Serial No. 361,129.

To all whom it may concern:

Be it known that I, HARRY F. BUSHONG, a citizen of the United States, residing at the city of Kalamazoo, county of Kalamazoo, State of Michigan, have invented certain new and useful Improvements in Temporary Binders or Loose-Sheet Holders, of which the following is a specification.

This invention relates to improvements in temporary binders or loose sheet holders.

This invention relates particularly to improvements in temporary binders or loose sheet holders such as is illustrated in my application for Letters Patent filed August 5th, 1904, Serial Number 219,624, and my application filed December 31, 1906, Serial Number 350,267, and is an adaptation of, and, in some respects, is an improvement upon the devices and inventions there illustrated and described.

The main object of this invention is to provide an improved temporary binder or loose sheet holder which is very simple and economical in structure and light in weight, and at the same time very efficient and very convenient to use.

Another object is to provide an improved temporary binder having flexible or light thin covers.

A further object is to provide an improved temporary binder adapted to receive any number of leaves, from its maximum to its minimum, which is capable of very rapid adjustment or manipulation for the purpose of removing or inserting the sheets or leaves.

Further objects, and objects relating to details of construction, will definitely appear from the detailed description to follow.

I accomplish the objects of my invention by the devices and means described in the following specification.

The invention is clearly defined and pointed out in the claims.

A structure embodying the features of my invention is clearly illustrated in the accompanying drawing, forming a part of this specification, in which,

Figure 1 is a detail view, partially in longitudinal section, taken on the line corresponding to line 1—1 of Fig. 2, of a structure embodying the features of my present invention, the binder being illustrated in its open position. Fig. 2 is a detail longitudinal section, taken on a line corresponding to line

2—2 of Fig. 1. Fig. 3 is a detail section of a modification of the binding cord adjusting means. Fig. 4 is a detail section of a further modification of the binding cord adjusting means, the rack 13 being substituted for the adjusting screw 10. Fig. 5 is a detail section of a modification of the structure shown in Fig. 4. Fig. 6 is a detail side elevation of the rack 14, of the structure shown in Fig. 5.

In the drawing, the sectional views are taken looking in the direction of the little arrows at the ends of the section lines, and similar numerals of reference refer to similar parts throughout the several views.

Referring to the drawing, the covers preferably consist of the inner chambered portions 1 formed of pieces of sheet metal folded upon themselves and outer portions 2, which may be flexible or made of thin material, clamped therein, or otherwise secured thereto. The chambered portions 1 of the covers are provided with end blocks 3, to which the sheet metal is secured, thereby forming a chamber at the inner end of each cover.

The cover extensions 2 are preferably secured by inserting them between the ends of the sheet metal parts 1 and riveting the same thereto. The covers are preferably provided with rigid projecting hinge members 5, to which the clamping bars 4 are secured by means of the pivots 5', thus permitting a free pivotal movement of the clamping bars, relative to the covers, and vice versa. The binding cords 7 are preferably formed in one piece, the same being inserted through the inner ends of the covers and the clamping bars, as clearly appears from the drawing.

In one of the covers, the binding cords, which are preferably in one piece, are looped about the bearing block 6 and its ends are secured to the nut 11 carried by the screw 10 arranged in the opposite cover. The screw 10 is arranged transversely of the cover, and preferably substantially parallel with the clamping bars, the end blocks 3 forming suitable bearings therefor. Guide pulleys 9 for the binding cords are located so as to guide the binding cords into the cover chamber, and a second guide pulley 8 is provided for one of the binding cords, so that it is properly guided to the nut 11 to effect the tightening or loosening of both binding cords at the same time.

The openings in the clamping bars for the

binding cords are of sufficient size and shape to allow full freedom of movement of the same.

By thus arranging and forming the parts, I 5 secure a binder which is very simple and economical in structure and one which may be made very light in weight, and, at the same time, is entirely effective for the purpose. It is capable of rapid adjustment and 10 is of considerable scope.

I have particularly designed my improved 15 binder as a slight or small binder or loose sheet holder, and it is particularly desirable for one having flexible covers, although it is obviously adapted to a stiff cover.

In the modification shown in Fig. 3, a pair 20 of nuts 11 is provided and the adjusting screw 10 is oppositely threaded. The structure shown in Figs. 1 and 2, is, however, preferred 25 by me, as a binder of the same dimensions is adapted to receive a greater number of leaves, and also is somewhat more economical to 30 produce.

In the structure shown in Fig. 4, I have 35 adapted the rack adjustment mechanism illustrated and described in my application for Letters Patent last above referred to. The rack bar 13 is mounted transversely of 40 the cover, substantially the same as the adjusting screw shown in Figs. 1, 2 and 3.

Both binding cords are, in this construction, 45 attached to the block 15, which is mounted on the rack bar 13, being guided thereto by pulleys, the same as shown in Fig. 1. The pawl 16, its spring 17, and the finger piece 18 are all preferably arranged as I illustrate and 50 describe in detail in the said application, and I do not, therefore, illustrate or describe the same in detail herein.

In Figs. 5 and 6, which are modifications of 55 the structure shown in Fig. 4, a double rack bar, as 14, is provided, the adjusting mechanism being the same as illustrated in Fig. 4 and the binding cords connected thereto the same as in the structure shown in Fig. 3.

I have illustrated and described my improvements in detail in the form preferred by me, and, on account of their structural simplicity, have shown several modifications 60 thereof. I am, however, aware that they are capable of still further modification.

Having thus described my invention, what I claim as new and desire to secure by Letters Patent is:

1. In a temporary binder or loose sheet holder, the combination of the covers, comprising the outer portions and the inner chambered portions, said inner chambered portions being formed of pieces of sheet metal folded to form the chambers; end pieces for said chambered portions; inwardly-projecting rigid hinge members on the inner ends of said covers; clamping bars pivotally-mounted on said hinge members; binding cords arranged through said clamp-

ing bars and the inner ends of said covers; a bearing block over which said binding cords are looped arranged in one of said cover chambers; a screw arranged in the opposite cover chamber parallel with the said clamping bars; bearings for said screw formed in the said end pieces for the chambered cover sections, said screw being arranged through one of the said end pieces; a nut to which said binding cords are secured arranged on 75 said screw; and guide pulleys arranged in the cover chamber containing said screw for guiding said binding cords to said nut whereby they are simultaneously tightened or loosened by the manipulation of the screw. 80

2. In a temporary binder or loose sheet holder, the combination of the covers, comprising the outer portions and the inner chambered portions, said inner chambered portions being formed of pieces of sheet metal folded to form the chambers; inwardly-projecting rigid hinge members on the inner ends of said covers; clamping bars pivotally-mounted on said hinge members; binding cords arranged through said clamping bars and the inner ends of said covers; a bearing block over which said binding cords are looped arranged in one of said cover chambers; a screw arranged in the opposite cover chamber parallel with the said clamping bars; a nut to which said binding cords are secured arranged on 90 said screw; and guide pulleys arranged in the cover chamber containing said screw for guiding said binding cords to said nut whereby they are simultaneously tightened or loosened by the manipulation of the screw. 95

3. In a temporary binder or loose sheet holder, the combination of the covers, comprising the outer portions and the inner chambered portions, said inner chambered portions being formed of pieces of sheet metal folded to form the chambers; end pieces for said chambered portions; inwardly-projecting rigid hinge members on the inner ends of said covers; clamping bars pivotally-mounted on said hinge members; binding cords arranged through said clamping bars and connected to one of said covers; a screw arranged in the opposite cover chamber parallel with the said clamping bars; bearings for said screw formed in the said end pieces for the chambered cover sections, said screw being arranged through one of the said end pieces; a nut to which said binding cords are secured arranged on 105 said screw; and guide pulleys arranged in the cover chamber containing said screw for guiding said binding cords to said nut whereby they are simultaneously tightened or loosened by 110 the manipulation of the screw. 115

4. In a temporary binder or loose sheet holder, the combination of the covers, comprising the outer portions and the inner chambered portions, said inner portions be-

ing formed of pieces of sheet metal folded to to form the chambers; inwardly-projecting rigid hinge members on the inner ends of said covers; clamping bars pivotally-mounted on 5 said hinge members; binding cords arranged through said clamping bars and connected to one of said covers; a screw arranged in the opposite cover chamber parallel with the said clamping bars; a nut to which said 10 binding cords are secured arranged on said screws; and guide pulleys arranged in the cover chamber containing said screw for guiding said binding cords to said nut whereby they are simultaneously tightened or loosened by the manipulation of the screw.

5. In a temporary binder or loose sheet holder, the combination of the covers, comprising the outer portions and the inner chambered portions, said inner chambered 20 portions being formed of pieces of sheet metal folded to form the chambers; end pieces for said chambered portions; clamping bars pivotally-connected to said covers; binding cords arranged through said clamping bars 25 and the inner ends of said covers; a bearing block over which said binding cords are looped arranged in one of said cover chambers; a screw arranged in the opposite cover chamber parallel with the said clamping 30 bars; bearings for said screw formed in the said end pieces for chambered cover sections, said screw being arranged through one of the said end pieces; a nut to which said binding cords are secured on said screw; and guide 35 pulleys arranged in the cover chamber containing said screw for guiding said binding cords to said nut whereby they are simultaneously tightened or loosened by the manipulation of the screw.

40 6. In a temporary binder or loose sheet holder, the combination of the covers, comprising the outer portions and the inner chambered portions, said inner chambered portions being formed of pieces of sheet metal 45 folded to form the chambers; clamping bars pivotally-connected to said covers; binding cords arranged through said clamping bars and the inner ends of said covers; a bearing block over which said binding cords are 50 looped arranged in one of said cover chambers; a screw arranged in the opposite cover chamber parallel with the said clamping bars; a nut to which said binding cords are 55 secured arranged on said screw; and guide pulleys arranged in the cover chamber containing said screw for guiding said binding cords to said nut whereby they are simultaneously tightened or loosened by the manipulation of the screw.

60 7. In a temporary binder or loose sheet holder, the combination of the covers, comprising the outer portions and the inner chambered portions, said inner chambered 65 portions being formed of pieces of sheet metal folded to form the chambers; end pieces for

said chambered portions; clamping bars pivotally-connected to said covers; binding cords arranged through said clamping bars and connected to one of said covers; a screw arranged in the opposite cover chamber parallel with the said clamping bars; bearings for said screw formed in the said end pieces for the chambered cover sections, said screw being arranged through one of the said end pieces; a nut to which said binding cords are 70 secured arranged on said screw; and guide pulleys in the cover chamber containing said screw for guiding said binding cords to said nut whereby they are simultaneously tightened or loosened by the manipulation of the 75 screw.

8. In a temporary binder or loose sheet holder, the combination of the covers, comprising the outer portions and the inner chambered portions, said inner chambered 80 portions being formed of pieces of sheet metal folded to form the chambers; clamping bars pivotally-connected to said covers; binding cords arranged through said clamping bars and connected to one of said covers; a screw 85 arranged in the opposite cover chamber parallel with the said clamping bars; a nut to which said binding cords are secured arranged on said screw; and guide pulleys in the cover chamber containing said screw for 90 guiding said binding cords to said nut whereby they are simultaneously tightened or loosened by the manipulation of the screw.

9. In a temporary binder or loose sheet holder, the combination of the covers, comprising the outer portions and the inner chambered portions, said inner chambered 100 portions being formed of pieces of sheet metal folded to form the chambers; end pieces for said chambered portions; leaf clamping 105 means; binding cords therefor arranged through the inner ends of said covers; a bearing over which said binding cords are looped arranged in one of said cover chambers; an adjusting screw for said binding 110 cords arranged in the opposite cover chamber parallel with the said clamping bars; and bearings for said screw formed in the said end pieces for the chambered cover sections, said 115 screw being arranged through one of the said end pieces.

10. In a temporary binder or loose leaf holder, the combination of the covers, comprising the outer portions and the inner chambered portions, said inner chambered 120 portions being formed of pieces of sheet metal folded to form the chambers; leaf clamping means; binding cords therefor arranged through the inner ends of said covers; a bearing over which said binding cords are 125 looped arranged in one of said cover chambers, and an adjusting screw for said binding cords arranged in the opposite cover chamber parallel with the said clamping bars.

11. In a temporary binder or loose sheet 130

- holder, the combination of the cover, comprising the outer portions and the inner chambered portions, said inner chambered portions being formed of pieces of sheet metal folded to form the chambers; end pieces for said chambered portions; leaf clamping means; binding cords therefor connected to one of said covers; an adjusting screw for said binding cords arranged in the opposite cover chamber parallel with the said clamping bars; and bearings for said screw formed in the said end pieces for the chambered cover sections, said screw being arranged through one of said end pieces.
15. 12. In a temporary binder or loose sheet holder, the combination of the covers, comprising the outer portions and the inner chambered portions, said inner chambered portions being formed of pieces of sheet metal folded to form the chambers; leaf clamping means; binding cords therefor connected to one of said covers; and an adjusting screw for said binding cords arranged in the opposite cover chamber parallel with the said clamping bars.
13. In a temporary binder or loose sheet holder, the combination of the covers, comprising the outer flexible portions and inner chambered portions, said inner chambered portions being formed of pieces of sheet metal folded to form the chambers and secured to the inner ends of the said outer cover portions; leaf clamping means; binding cords therefor connected to one of said covers; and adjusting means for said binding cords arranged in the opposite cover chamber.
14. In a temporary binder or loose sheet holder, the combination of the covers comprising the outer flexible portions and the inner chambered portions, said inner chambered portions being formed of pieces of sheet metal folded to form the chambers and secured to the inner ends of the said outer cover portions; leaf clamping means; binding cords therefor connected to one of said covers; and adjusting means for said binding cords arranged in the opposite cover chamber.
15. In a temporary binder or loose sheet holder, a cover, comprising an outer flexible portion and an inner chambered portion, said inner chambered portion being formed of a piece of sheet metal folded to form the chamber and clamped upon the inner end of the said outer cover portion and secured thereto.
16. In a temporary binder or loose sheet holder, a cover, comprising an outer portion and an inner chambered portion, said inner chambered portion being formed of a piece of sheet metal folded to form the chamber and clamped upon the inner end of the said outer cover portion and secured thereto.
17. In a temporary binder or loose sheet holder, a cover, comprising an outer flexible portion and an inner chambered portion, said inner chambered portion being formed of a piece of sheet metal folded to form the chamber secured to the inner end of the said outer cover portion.
18. In a temporary binder or loose sheet holder, a cover, comprising an outer portion and an inner chambered portion, said inner chambered portion being formed of a piece of sheet metal folded to form the chamber secured to the inner end of the said outer cover portion.
19. In a temporary binder or loose sheet holder, the combination of the covers having chambers at their inner ends; clamping bars pivotally-connected to said covers; binding cords arranged through said clamping bars and the inner ends of said covers; a bearing over which said binding cords are looped arranged in one of said cover chambers; a screw arranged in the opposite cover chamber parallel with the said clamping bars; a nut to which said binding cords are secured arranged on said screw; and guide pulleys arranged in the cover chamber containing said screw for guiding said binding cords to said nut whereby they are simultaneously tightened or loosened by the manipulation of the screw.
20. In a temporary binder or loose sheet holder, the combination of the covers having chambers at their inner ends; clamping bars pivotally-connected to said covers; binding cords arranged through said clamping bars and connected to one of said covers; a screw arranged in the opposite cover chamber parallel with the said clamping bars; a nut to which said binding cords are secured arranged on said screw; and guide pulleys in the cover chamber containing said screw for guiding said binding cords to said nut whereby they are simultaneously tightened or loosened by the manipulation of the screw.
21. In a temporary binder or loose sheet holder, the combination of the covers having chambers therein; clamping bars pivotally-connected to said covers; binding cords arranged through said clamping bars and the inner ends of said covers connected to one of said covers; an adjusting means for said binding cords arranged in the opposite cover chamber transversely of the covers; and guide pulleys arranged in the cover chamber containing said adjusting means for guiding said binding cords thereto, whereby they are simultaneously tightened or loosened.
22. In a temporary binder or loose sheet holder, the combination of the covers, one of said covers having a chamber therein; clamping bars pivotally connected to said covers so that said covers and clamping bars may move independently in the opening or closing of the binder; binding cords connected to one of said covers; and an adjusting means for

said binding cords arranged in the opposite cover chamber transversely of the cover.

23. In a temporary binder or loose sheet holder, the combination of the covers; leaf-
5 clamping means; binding-cords therefor connected to one of said covers; an adjustable member to which said binding-cords are connected, arranged to be adjusted transversely on the other cover; pulleys for guiding said 10 binding-cords; and adjusting means therefor whereby said binding-cords may be simultaneously tightened or loosened.

24. In a temporary binder or loose sheet holder, the combination with the covers hav-
15 ing chambers in their inner ends, of clamping bars pivotally connected to said covers; binding cords arranged through said clamping bars and the inner ends of said covers; a bearing over which one of said binding cords 20 is looped arranged in one of said cover chambers; and an adjusting means for said bind-

ing cords arranged in the opposite cover chamber transversely of the covers.

25. In a temporary binder, the combina-
tion with the leaf clamping members of bind-
ing cords; an adjusting mechanism therefor comprising a screw-threaded shaft arranged 25 parallel with said clamping members; a nut to which said binding cords are secured, ar-
ranged on said shaft; and guide pulleys for 30 guiding said binding cords to said nut, where-
by they are simultaneously tightened or loosened by the manipulation of the said screw shaft.

In witness whereof, I have hereunto set 35
my hand and seal in the presence of two
witnesses.
